W. E. EWART

TWO-CYCLE GAS ENGINE

Filed March 5, 1923

Patented Dec. 1, 1925.

1,563,733

UNITED STATES PATENT OFFICE.

WILLIAM E. EWART, OF RAYMOND, WASHINGTON.

TWO-CYCLE GAS ENGINE.

Application filed March 5, 1923. Serial No. 622,814.

To all whom it may concern:

Be it known that I, WILLIAM E. EWART, a citizen of the United States, residing at Raymond, county of Pacific, and State of Washington, have invented a new and useful Two-Cycle Gas Engine; and I do hereby declare that the following is a full, clear, and exact specification, such as will enable others skilled in the art to which it appertains to make and use the same.

The invention is an engine having a power cylinder, and a scavenger cylinder, with a sleeve piston so constructed as to form a smaller piston in said sleeve piston, same piston being enlarged at one end, to form a larger piston for scavenger cylinder and a smaller piston to work within cylinder of said piston.

The object of the invention is to get the maximum of power in a minimum of space and weight.

Another object of the invention is to provide a spark plug and means for operating it which may fire gases in a cylinder formed inside of a piston.

And another object of the invention is to provide an engine having three chambers on the same center line, two of which transmit power from explosions to the crank shaft and the other a scavenger cylinder.

With these ends in view the invention embodies an engine having one piston inside of the sleeve piston of the outer cylinder and an enlarged cylinder at the lower end of the smaller; and a means for admitting, exploding and discharging gases to and from the smaller cylinders.

Other features and advantages of the invention will appear from the following description taken in connection with the drawings wherein:

Figure 1 is a cross section on the center line of the engine showing the larger piston in the upper position and the inner piston in the lower position.

Figure 2 is a similar section with the pistons reversed.

Figure 3 is a detail showing the means for operating the spark plugs in the inner cylinder.

In the drawings I have shown my engine as it would be constructed wherein numeral 1 indicates the outer cylinder, numeral 2 the sleeve piston, numeral 3 the scavenging cylinder, numeral 4 the piston in the enlarged

cylinder, numeral 5 the inner piston, and numeral 6 the scavenging piston.

The large or main cylinder 1 may be constructed as shown with an intake valve 7, a spark plug 8; and an exhaust port 9, an opening 10 which admits gas to the inner cylinder, and another opening 11 through which the gas from the inner cylinder may exhaust.

The inner sleeve piston 2 may be constructed as shown with an intake valve 12, a spark plug 13 and exhaust openings 14 through which the exploded gases may pass to the openings 11 in the casing of the cylinder 1.

At the lower end of the cylinder 1 is the scavenging cylinder 3, which has an intake opening 15 at one side of its upper end, and a discharge opening 16 at the other side.

The sleeve piston 4, in the cylinder 1, may be constructed as shown with an opening 17 in its upper end, in which is the stem and spring of the valve 12. At the upper end of this opening is a plug 18 which may be removed when it is desired to adjust or replace the valve. Around the upper end of the cylinder are piston rings 19, which may be arranged as shown, or may be placed at any desired points in the piston. In this end of the piston is also an opening 20 which extends completely around it, thus separating the head of the piston from the body, or skirt, with the exception of the lugs 21 which tie them together. It will be seen that as the opening 10 extends completely around the cylinder, gas may pass from it through the opening 20, to the valve 12, which will admit it to cylinder 2 when the pistons are in the position shown in Figure 1.

In one side of the piston 4 and in the opening 20 is a lug 22, into which the spark plug 13, may be screwed, and at this point is a large opening 23 for the head of the spark plug, and a recess 24 for the operating means as shown in Figure 3. In this recess is a contact bar 25, which is insulated from the piston by the non-conducting material 26, and held to it by a screw 27. The bar 25 engages a roller 28 on the end of a cylinder 29, which is slidably mounted in an opening 30 and constantly held against the bar by a spring 31. The cylinder 29 is held in tube 32 and this is insulated from the casing of the main cylinder by the non-conducting material 33. A cap 34 which also may be made of a non-conducting material, may

be placed on the outside casing to hold the cylinder in place, and also to form a bearing for a stem 35 projecting from the cylinder. A contact wire may be attached 5 to the outer end of the stem, and this may lead to a timer, or any suitable means for operating the spark plug.

The piston 5 may be constructed in a manner similar to that of an ordinary piston, 10 with a wrist pin 36 in it by which it is connected through the connecting rod 37, to the offset section 38, of the crankshaft 39.

The scavenging piston 6 may be placed on the lower end of the piston 4, and may have 15 two connecting rods, 41 and 42, connecting it and the piston 4, through the wrist pins 43 and 44, to the offset sections 45 and 46 of the crankshaft 39. It will be seen that the force of the explosion will be transmitted 20 from the cylinder 1, through the connecting rods 41 and 42 to the crankshaft.

It is understood that the cylinder 1 may be made of any desired design and both it and the piston 4 may have water jackets 47 25 in them for keeping them cool. The valves for admitting gases to and from the cylinders and also for admitting air to and from the scavenging cylinder may be of any suitable design, and may be operated in any desired manner. The spark plugs and the means for operating them may also be of 30 any desired design.

It is understood that other changes may be made in the construction without departing 35 from the spirit of the invention. One of which changes may be in the length of the stroke, another may be in the design or size of the pistons or cylinders, and still another may be in the use of more of the units shown 40 on the same crankshaft.

The construction will be understood from the foregoing description. To use the engine it may be assembled as shown. And when 45 an explosion occurs in the upper cylinder 1, the piston in this cylinder will be forced downward, and at the same time the smaller or inner piston 5 will move upward, so that it will compress gas in sleeve piston 2, at the same time air will be drawn into the 50 scavenger cylinder 3, through the intake 15.

Then when they arrive at the position shown in Figure 2, the gas in the inner cylinder 2 will be exploded and this will force piston 5 downward and pistons 4 and 6 upward, and the connecting rods from both the pistons will transmit the power to the crank-shaft. The air in the scavenger cylinder will be forced through the discharge port 16 and into a tank from where it may be connected by any suitable means to the intake valves of the explosion chambers. These valves may be operated by any suitable means so that they will admit this compressed air to the exhausting chambers just before they have arrived at the lower end 65 of their strokes. It will be seen that with an engine of this type it will be possible to concentrate the force or practically a double cylinder into one cylinder and also to thoroughly cleanse the cylinder of the burnt 70 gases.

Having thus fully described the invention what I claim as new and desire to secure by Letters Patent is:—

1. A two-cycle engine having a piston 75 within a sleeve piston, an outer cylinder, an enlarged cylinder, an enlarged piston depending from said sleeve piston, connections between said pistons to crankshaft, intake valves to said outer cylinder and to said sleeve piston, an annular row of intake ports on said sleeve piston and leading to its inlet valve, exhaust ports in said cylinder and sleeve piston, an explosive chamber within the outer cylinder and also within said sleeve 85 piston and above said inner piston.

2. In a two cycle engine, having a piston within a sleeve piston, an outer cylinder, an enlarged cylinder, an enlarged piston depending from said sleeve piston, connections 90 between said pistons to a crank shaft, intake valves to said outer cylinder and to said sleeve piston, intake ports on said sleeve piston and leading to its inlet valve, exhaust ports in said cylinder and sleeve piston, an explosive chamber within the outer cylinder, and another explosive chamber within the 95 said sleeve piston and above the said inner piston.

WILLIAM E. EWART.
